[57] CLAIM

The ornamental design of a housing for an electrically operated jack, substantially as shown and described.

DESCRIPTION

FIG. 1 is a perspective view of a housing for an electrically operated jack showing our new design;

FIG. 2 is a right side elevational view thereof with the opposite side being a mirror image thereof;

FIG. 3 is a front elevational view thereof;

FIG. 4 is a rear elevational view thereof; and,

FIG. 5 is a top plan view thereof.

The undisclosed bottom portion is planar and unornamented.

The broken line showing of a jack shaft is for illustrative purposes only and forms no part of the claimed invention.
